BY

E. G. Silvius,

ATTORNEY.

UNITED STATES PATENT OFFICE

AUGUST H. OPPERMANN, OF INDIANAPOLIS, INDIANA

HAIR-WAVING APPARATUS

Application filed March 17, 1928. Serial No. 262,367.

This invention relates to structural improvements in equipment and facilities adapted to be used in the operations of curling or waving hair by the application of heat, the general nature of which is explained in my application for Letters Patent filed October 26, 1927, Serial Number 228,902, the present application disclosing a modification of said application for Letters Patent; the present invention having reference more particularly to improvements in the means for adjustably supporting and controlling a large number of electric heaters whereby the operations of waving human hair are expeditiously performed.

An object of the invention is to provide an improved stand of electric heaters for hair-waving operations which shall be of such construction as to be adapted to operate advantageously and efficiently.

Another object is to provide improved means for adjustably supporting the necessary electric heaters without depending upon electric circuit wires for their support, which adjusting means shall be of such construction as to permit rapid assembly of parts and replacement of parts which may become necessary as a result of long use and wear.

A further object is to provide a self-contained unit of adjusting devices whereby to support the electric heaters in a convenient, time-saving and ornamental manner and which shall not be costly to manufacture and shall be durable and economical in use.

With the above-mentioned and other objects in view, the invention consists in an improved dome and a novel unit of guiding means removably mounted therein, the invention consisting also further in the parts and combinations and arrangements of parts as hereinafter particularly described and further defined in the accompanying claims.

Referring to the accompanying drawings,—Figure 1 is a side view, approximately one-half in elevation and the remainder in central section, the supporting stand thereof being partially broken away; Fig. 2 is a bottom plan and half section taken adjacent to the bottom of the supporting dome, portions being broken away; Fig. 3 is a fragmentary

vertical central section of the improved dome and parts of the unit of adjusting devices therein, on an enlarged scale; Fig. 4 is a fragmentary elevation more clearly showing an assembly of adjusting means for the heaters on a further enlarged scale; and Fig. 5 is a fragmentary sectional detail clearly showing improved structural features of the dome on an enlarged scale.

Similar reference characters in the various figures of the drawings indicate corresponding elements or features of construction herein referred to in detail.

The improved hair waving apparatus comprises a suitable base 1 and a standard main part 2 secured thereto and having a pipe cross 3 on its top to which a curved arm 4 is secured and then reaches laterally a suitable distance, the end of the arm having a knob 5 thereon provided with a downward extending neck 6. 65 An improved hollow dome is provided which comprises a central crown portion 7 that is arranged against the end of the neck 6, and an out-spreading cover portion 8 having a cylindrical shell portion 9 extending downward therefrom and connected with a side branch 10 of the pipe cross 3 for support, the branch being adapted to cover electric wiring. The cross has a lateral branch 11 into which 70 an electric circuit wire cable 12 extends that has a plug 13 thereon for connection with a service socket. The dome has an inclined section 14 which has a suitable connection 15, permanent or detachable as may be desired, with the cylindrical portion 9 from which it extends inwardly to form a side portion or a bottom part of the dome if so preferred. The part 14 has a plurality of guide bushings 16 set therein to smoothly guide heater supporting cords. As preferably constructed the 75 part 14 has a downward extending neck portion 17 provided on its lower edge with an inward extending seat portion 18 provided with a suitable number of projecting studs 19.

The dome has a central hanger post 20, 95 preferably tubular, that extends through the crown portion 7 and is screwed into the neck 6, the post being of suitable length to extend downward considerably lower than the connection 15. A nut 21 is screwed onto the 100

upper portion of the post against the crown portion 7 to rigidly secure the parts together, and the lower end of the post has a projecting screw-thread stud 22 suitably fixed thereon.

The dome has a unitary adjusting apparatus mounted therein so as to be readily removed or replaced and as preferably constructed comprises a top frame plate 23 and a bottom frame plate 24 to which a suitable number of guide rods 25 are connected, each of the rods having a nut 26 thereon that engages the top of the plate 23, the rods extending through the plate 24, a number of the rods having each a nut 27 on its lower portion engaging the under side of the bottom plate. The top plate 23 is adapted to slide over the post 20, having a suitable central hole to receive the post, and the plate 24 has a suitable central hole to receive the stud 22 over which the plate may be slipped into contact with the lower end of the post to be secured in place by means of a nut 28 screwed onto the stud. Each guide rod has a guide base 29 thereon arranged on the under side of the plate 23 and supporting a cord guide 30 and preferably a similar guide 31, said guides preferably being composed of wire integral with the base, the base being secured in place by means of a nut 32 on the rod. Preferably each guide rod has a noise-silencer washer 33 thereon in engagement with the nut 32, and each rod has also a similar washer 34 thereon in contact with the top of the bottom plate 24. Also those rods that have nuts 27 thereon have also a nut 35 on the upper side of the plate 24 beneath the washer. A plurality of weights 36 are provided, one on each guide rod, each weight preferably having a lining tube 37 fixed therein that has sliding contact with the guide rod. The top of each weight is provided with an eye 38 and preferably a cord guide 39 in the form of an eye. A suitable number of cords 40 are provided and each cord is connected to the eye 38 and reeved through the guide 30, thence through the guide 39, thence through the guide 31 and thence through a guide bushing 16, each cord being connected to and adjustably supporting a hollow electric heater 41 of conventional or suitable construction.

The dome has a removable bottom part which preferably comprises a saucer-shaped central member 42 that is suitably connected to the stud 22 and secured in place by a cap nut 43 screwed onto the stud. The marginal portion of the member 42 has a ledge 44 assisting to support the plate 24, and an out-spreading side portion 45 connected with the ledge and having a bench portion 46 thereon that preferably extends slightly upward and has a joint flange 47 thereon adapted to embrace the neck 17, the bench portion having suitable holes to receive the studs 19 on which cap nuts 48 are screwed to secure the bottom part to the top part of the dome. A suitable

number of electric connecting plug receptacles 49 are secured to the bench portion 46, plugs 50 being removably connected to the receptacles and having electric circuit wire cords 51 connected thereto, usually two to a plug, each cord being connected with a heater 41, and the bench has also a lamp socket 52 mounted thereon to hold a lamp bulb. An electric switch 53 is mounted on the bench portion 46 conveniently near to the branch 10. 75

The circuit wires for conducting electric current to the conducting cables 51 are not shown, obviously it being conventional to properly connect the receptacles together and with the switch and the cable 12. 80

Since the frequent adjustments of the cords 40 may be necessary in operation the cords may require replacements which may be rapidly accomplished when the bottom part of the dome is removed from place and the adjustment apparatus unit is lowered and separated from the hanger post, so that the old cords may readily be disconnected from the weights and new cords connected thereto and reeved through the cord guides and easily brought through the guides 16, various parts being readily accessible. 85

In practical use the electric heaters are drawn down to the subject to be treated who may be seated under the dome, and strands of hair are suitably arranged in the heaters, the electric conducting cables being more or less slack while the cords are kept taut by the adjusting weights to support the heaters and prevent them from tilting over from the desired positions. The weights 36 are sufficient with the aid of gravity to draw up the slack in the cords when the heaters are manually lifted, the cord guides affording frictional resistance sufficient to prevent lifting of the weight by the weight of the heaters when they are released. Thus the heaters are adjustably supported at the desired levels and may be readily readjusted as may be desired. 100

What is claimed is:

1. A hair-waving apparatus having a dome and a self-contained adjusting apparatus unitarily supported therein for ready removal, the adjusting apparatus including cords and weights thereon, guide rods for the weights, and guides for the cords. 110

2. A hair-waving apparatus having a dome and a unitary adjusting apparatus including two spaced apart frame plates, guide rods connecting said plates, the plates being removably supported in the dome, weights movable on the rods, cords connected to the weights, and cord guides on the rods adjacent to one of the plates. 120

3. A hair-waving apparatus having a dome with a center-post and a unitary separately portable adjusting apparatus located in the dome and including two separated frame plates, one of the plates being detachably secured to the center-post, a plurality of guide 125

rods connecting the plates, weights movable on the rods respectively, cord guides supported by the rods respectively, cord guides secured to the dome, cords connected to the 5 weights and guided by the guides, and electric heaters supported by the cords.

4. A hair-waving apparatus including a dome having a crown part, a hanger post centrally secured at its top to the crown part and 10 having a projecting stud on its lower end, a unit frame removably arranged on the hanger post and having guide rods and cord guides, weights movable on the rods, cords extending through the cord guides and connected to the 15 weights, a device to detachably secure the unit frame to the hanger post, and a dome bottom part detachably secured to the crown part and also to the unit frame by means of said stud.

20 5. In a hair-waving apparatus, a hollow dome comprising a cover part having a central crown portion and an outspread main portion and also a cylindrical portion extending downward from the main portion, an 25 inclined side part secured to said cylindrical portion, a post centrally secured to said crown portion and having a projecting stud on its lower end, and a bottom part comprising a central portion detachably secured to 30 said stud and a deep side portion and also a bench portion detachably secured to said inclined side part, said bench portion having electric plug receptacles thereon.

35 6. In hair-waving apparatus, the combination of a sectional hollow dome, a post secured to the upper and lower sections of the dome, a unit frame within the dome and comprising two separate plates and guide rods secured thereto, the rods connecting the 40 plates together, the upper one of said plates being guided on said post and the lower one of the plates detachably secured to the post, guide eyes mounted on the upper portions of 45 said rods, weights movable on said rods, and cords connected to the weights and extending through said eyes.

50 7. In a hair-waving apparatus, the combination of a dome comprising a crown part and a hanger post secured thereto, the dome having a bottom part secured to the post, a frame within the dome detachably secured to the post and having guide rods and cord guides, weights movable on the guide rods, flexible cords connected to the weights and 55 reeved through the cord guides, the cords being also guided by the dome, and electric heaters connected to the cords.

60 8. In a hair-waving apparatus, the combination of a hollow dome and a unitary counterbalancing system arranged therein, said system comprising a pair of spaced members, a plurality of rods connecting said members, a weight slidably guided by each rod, a cord 65 supporting each weight and cord guide

means adjacent to the upper end of each rod over which means the respective cord is trained, said dome being provided with spaced passages through which the respective cords pass from said guide means to the 70 exterior of the dome.

9. A structure such as described in the immediately preceding claim in which the weights have cord guides and in which the cords are secured at their inner ends to one 75 of said spaced members and then so trained through the respective guide means and guides of said system as to permit the free ends to move through a greater distance than the associated weights.

In testimony whereof, I affix my signature on the 18th day of March, 1928.

AUGUST HENRY OPPERMAN.
